UNITED STATES PATENT OFFICE.

THOMAS G. HITT, OF SEATTLE, WASHINGTON.

FIRECRACKER.

Application filed January 25, 1926. Serial No. 82,542.

This invention relates to fire crackers, and particularly to the process of constructing a firecracker with a charge of explosive confined between the closed ends of an inner and outer tubular member, and also the finished product of such fire crackers.

The objects of the invention are to provide a rapid process for assembling the several parts of a fire cracker, and to provide 10 a fire cracker with the explosive charge securely confined within its predetermined chamber with a double fuse connection from the outside into contact with the said charge.

A further object is to form a fire cracker 15 with a pressed tube closed at one end from one piece of material, and a charge of explosive in the tube near the closed end thereof, and to confine the charge in such position by a secondary tube also made by pressing 20 the same into shape with one end closed and the outer diameter or periphery thereof of such size as to be slidably adjusted tightly within the first tube with the closed end of the secondary tube pressed against the 25 charge, and to provide longitudinal grooves along the opposite sides of the secondary tube within which the two ends of a fuse are adjusted, with the loop connecting part of the fuse ends bent over the closed end of the 30 secondary tube and embedded in the charge.

My invention is illustrated by the accompanying drawings, in which Figure 1 represents a front elevation of the secondary tube or plug; Figure 2 represents a similar view 35 of the plug with the fuse adjusted; Figure 3 represents the assembled fire cracker, and Figure 4 represents the assembled fire cracker in section. Figure 5 is an end view of the assembled fire cracker.

40 Like numerals on different figures represent like parts.

In the process of constructing my fire cracker I prepare a tubular chamber or explosive container with one end of the tube securely closed, either by compressing the 45 end closure inward from the edges of the end to be closed, and more preferably by forming the entire container from a flat piece of tough pasteboard or card board 50 which I do by pressing the center of the section of such material by a plunger operated over a suitable opening of the diameter for which the outer periphery of the tube is 55 designed until the proper length of tube has been formed, with the closed end of substantially its original thickness, and the side-

walls of same or slightly less thickness. I then prepare a secondary tube of same material and by same process, with the periphery of the secondary tube or plug of substantially the same dimensions as the inner diameter of the container tube, so that the secondary tube or plug member can be pushed into the first tube or container.

The secondary tube or plug member is 60 prepared with longitudinal grooves one on each side opposite the other, which grooves are preferably formed as the tube is being pressed from flat section of material, the plunger being provided with grooves on each 65 side and the opposite sides of the opening or female member being provided with corresponding ribs to force the sides of the tube into the grooves of the plunger. I then insert a proper amount or charge of explosive 70 into the container tube and adjust over the closed end of the plug or secondary tube a section of ignition fuse with the loop or central part of the fuse across the closed 75 end of the plug and the sides of the fuse or extending ends in the grooves on each side of the plug, and then insert and press the plug or secondary tube into the open end of the container till the closed end of the plug is 80 pressed tightly against the charge, with the 85 bend of the fuse embedded in the charge for certainty of igniting the same as the fuse is fired.

This process of assembling the previously 90 prepared parts, is very rapid, safe, the finished product highly satisfactory. The container may be formed of material of sufficient thickness to so strongly restrain the explosive that a loud report will be caused at the time of explosion, and may be further reinforced by any ordinary outer tubular shell into which it may be inserted to 95 any desired position, with the two ends of the fuse extending therefrom for lighting.

The several parts are further specified by 100 the numerals, as 1, the secondary tube or plug in finished condition, with the oppositely positioned longitudinal grooves 2 of suitable size for containing the ordinary ignition fuse 3 for firecrackers, which is 105 bent over the closed end 4 of the tubular plug.

5 represents the tubular container with one closed end 6, and a charge of suitable explosive 7, with bend 3^a of the fuse pressed 110 down into the charge and the closed end of the plug member firmly pressed against the

charge. 8 represents any ordinary tubular body shell open at both ends into which the container may be inserted to any desired position in the shell or outer body. The 5 plug member is preferably shorter than the container, so that when the closed end of the plug is seated upon the charge, the open end of the plug is even with the open end of the container.

10 By providing the grooves along the walls of the tubular member plug, the fuse is in no place so tightly compressed that the fire will become choked thereby, as frequently occurs in the ordinary methods and 15 formation of fire crackers, and at the same time the container tube and the plug member may be so snugly adjusted the one within the other that no loss of explosive force can occur between them. The loop portion 20 of the fuse being bent over the closed end of the plug when inserted, assures that it will be pressed against the charge, and the same fired by igniting either of the fuse ends.

25 Having described my invention, I claim—
1. A firecracker, with a tubular container with one end thereof closed by a part thereof, with a charge of explosive therein, and

a tubular plug with one end closed by a part thereof, and longitudinal grooves 30 along opposite sides of the plug, and a fuse bent over the closed end of the plug and the two ends of the fuse placed in the grooves and the plug pressed into the container with the closed end of the plug 35 seated against the charge and the bend of the fuse embedded in the charge, and the extended ends of the fuse protruding from the container, for ignition.

2. A firecracker comprising an explosive 40 container made from suitable material in tubular form with one end closed by an integral part of the material, and an inner compression tube made from suitable material with one end thereof closed by an 45 integral part of the material thereof, with a charge of explosive inside the container between the closed end thereof and the closed end of the compression member, with a fuse extending from the charge of explosive outward between the walls of the tubular members from the charge of explosive to the open ends of the tubes.

In testimony whereof I affix my signature.

THOMAS G. HITT.
